UNITED STATES PATENT OFFICE.

EDWARD McCLOSKEY, OF COLUMBUS, OHIO, ASSIGNOR, BY DIRECT AND MESNE ASSIGNMENTS, OF PART TO JOHN W. HARRIS, OF SAME PLACE, WILLIAM McCLOSKEY, OF PITTSBURG, PENNSYLVANIA, AND JOHN B. FOLEY, OF STEUBENVILLE, OHIO.

CAR-COUPING.

SPECIFICATION forming part of Letters Patent No. 356,204, dated January 18, 1887.

Application filed August 7, 1886. Serial No. 210,354. (No model.)

To all whom it may concern.

Be it known that I, EDWARD McCLOSKEY, a citizen of the United States, residing at Columbus, in the county of Franklin and State 5 of Ohio, have invented a certain new and useful Improvement in Car-Couplings, of which the following is a specification.

My invention relates to improvements in automatic car-couplers; and the objects of my 10 invention are to produce a draw-bar provided with an effective coupling device of this class which will obviate the necessity of going between the cars to couple or uncouple the same. These objects I accomplish in the manner 15 illustrated in the accompanying drawings, in which—

Figure 1 is a plan view of the ends of two flat-cars coupled by my device. Fig. 2 is a perspective view of one of the draw-heads. 20 Fig. 3 is a side elevation of the coupling-lever and a transverse section of the operating-rod. Fig. 4 is a view of the under side of the draw-bar and the mechanism for operating the same; and Fig. 5 is a detail view of the brake-shaft, showing its connection with the operating-rod.

Similar letters refer to similar parts throughout the several views.

A represents the draw-bar, having an end 30 and partially circular head, consisting of two curved jaws, a a' , the jaw a' extending about one-half the distance of the jaw a , the latter being extended sufficiently to cause its outer surface to form nearly one-half of a circle. The inner side of the shorter jaw, a' , is curved to conform to the curve of the outer side thereof, said inner curve extending rearwardly and inwardly until a point about the center of the width of the draw-bar is reached.

40 The inner surface of the jaw a is provided with a vertical groove, a^2 , the curve of which conforms to the curve of the outer surface of the jaw. Said groove extends within a short distance of the rear terminus of the inner 45 curve of the short jaw a' , to which latter point extends a rearward and slightly-curved cut, as shown.

The jaw a is provided with a horizontal opening or slot, c , about the middle of its

height, through which is made to pass a short 50 arm, d , having on its inner end a half-cylindrical locking-block, b , the convex surface of which bears against and fits within the vertical groove a^2 of the jaw a .

The arm d , extending obliquely outward 55 through the slot c , is pivoted, by means of a pivot-bolt, f , to one end of a rearwardly-projecting rod, g , which extends beneath the car and bears loosely within a downwardly-projecting bearing-arm, h , secured to the bottom 60 of the car, said arm also forming a bearing for the head of a spiral spring, i , made to surround the rear portion of the rod, and having its rear end bearing against a nut on the rear end of the rod.

65 The tension of the spring i tends to keep the arm d in an oblique position, thus causing the locking-block b to turn in its groove a^2 sufficiently to make its rear edge project slightly beyond the rear edge of said groove. 70

Pivoted to the rod g , at a point in front of the bearing h , is the inner end of a lever, k , which extends laterally outward slightly beyond the side of the car, and is pivoted loosely with a bearing-stirrup, m , made to project 75 downwardly from the bottom of the car.

Rigidly secured to the lever k , preferably at a point within the stirrup m , is the lower end 80 of a vertical brake-shaft, n , which is made to extend upwardly above the top of the car, having suitable bearings in or projecting from the end of the car. Where the brake-shaft n meets the top of the car, it is provided with a small ratchet-wheel, o , with the teeth of which is adapted to engage the loose end of a pawl, 85 p , pivoted to the top of the car.

The rear end of the draw-bar is secured in the usual manner beneath the car, and is provided at its rear end with the usual spiral spring, q .

90 The outer end of the jaw a is made rounding, and is provided with a vertical coupling-pin hole. The rounded perforated end thus formed is provided with a central transverse cut or slot, r .

The heads of the draw-bars and the operating mechanism above described being alike on the various cars, a coupling is formed by bring

ing the draw-heads together, allowing the jaw a of one head to extend within the open jaws of the other, and to bear against the inner curved surface of the short jaw a' until its 5 end reaches the shoulder formed in the rear of the other jaw a . The rounded ends of the jaws a as they enter strike against the rear projecting edges of the locking-block b and force them back into their seat within the 10 grooves a^2 , where they remain until said rounded ends of the jaws a have extended sufficiently inward to allow the blocks to resume their normal position, thus bringing their projecting edges in rear of the ends of 15 the jaws a and preventing the latter from escaping therefrom. By pressure on the outer end of the lever k the locking-blocks b are again forced, by means of the rod g and arm d , into their seats in the grooves a^2 , and the inter- 20 locked parts of the coupling may readily be disengaged. The parts may also be disengaged, in case the brakeman is on top of the car, by operating the rod g and its connecting parts through the brake-shaft n . 25 In case it is desired to set the coupling device so that it will fail to interlock with the couplers of other cars, the brake-shaft n may be revolved, as described, and the pawl p be made to engage with the teeth of the ratchet- 30 wheel o , and thus hold the locking-block in the desired position. The same object may be accomplished by hooking the outer end of the lever k to a suitable pendent hook beneath the side of the car. 35 Should it become necessary to couple a car having the above-described draw-bar to one having the well-known form of link and pin, the link may be inserted within the slot r of the jaw a and be held therein by means of a 40 common coupling-pin, s , made to pass through the vertical hole in the outer end of said jaw.

The parts herein described are so made as to allow for such play as might be made necessary by the curve or unevenness of the track.

I am aware that locking-blocks have been 45 used before with similar operating mechanism; but my invention differs from these in having combined therewith the peculiarly-shaped jaws, which add great strength to the device. I therefore do not claim said locking-blocks 50 and operating mechanism, broadly; but

What I do claim, and desire to obtain by Letters Patent, is—

1. In a car-coupling, the combination of the draw-bar A , having the curved jaws a' and a , 55 the latter having a slot, c , with the locking-block b , its arm d , spring-actuated rod g , and lever k , pivoted to said rod, substantially as and for the purpose specified.

2. In a car-coupling, the combination of the 60 draw-bar A , having the curved jaws a' and a , the latter having a slot, c , with the locking-block b , its arm d , spring-actuated rod g , lever k , pivoted to said rod, and brake-shaft n , 65 secured to said lever and having a ratchet-wheel, o , with the teeth of which the pawl p is adapted to engage, substantially as and for the purpose specified.

3. The combination of the draw-bar A , having the curved jaws a' and a , the latter having 70 a longitudinal slot, c , and a transverse cut or slot, r , and a vertical pin-hole in its outer end, with the locking-block b , its arm d , spring-actuated rod g , lever k , pivoted to said rod, and brake-shaft n , secured to said lever and 75 having a ratchet-wheel, o , with the teeth of which the pawl p is adapted to engage, substantially as and for the purpose specified.

EDWARD McCLOSKEY.
